UNITED STATES PATENT OFFICE.

DANIEL J. RING, OF QUINCY, MASSACHUSETTS.

GARTER.

1,046,493.

Specification of Letters Patent. Patented Dec. 10, 1912.

Application filed December 7, 1911. Serial No. 664,317.

To all whom it may concern:

Be it known that I, DANIEL J. RING, of Quincy, in the county of Norfolk and State of Massachusetts, have invented a new and 5 useful Garter, of which the following is a specification.

The main object of my invention is to provide a garter which will efficiently engage the stocking and which at the same 10 time will be simple and inexpensive.

The main feature of my invention is the use of a cord member which engages the stocking and also clamps itself to the stocking.

15 Other features of the invention will be pointed out below.

In the drawings, Figure 1 is a diagrammatic view showing the garter in place on the leg: Fig. 2 is a front elevation enlarged 20 of the stocking engaging members: Fig. 3 is a central section of the same; and Fig. 4 is a rear elevation of the same.

The main gripping member is preferably 25 of leather or similar material and has a flat body portion A and also has an off-set projection consisting of a head a, a projecting lip a' and groove a² to engage the stocking. It is also provided with a headed stud 30 consisting of shank a³ having a head a⁴ for a purpose hereinafter pointed out. It has an inclined passage from its rear face at x leading through to its front face and has a passage a⁵ leading from its front to its rear 35 face, this passage being slightly to one side of the longitudinal central line of member A. I also provide grooves a⁶ a⁷ in the sides of member A for a purpose later described.

Member B is preferably a cord, knotted 40 at one end to engage the rear face of member A at x, and extending thence through the inclined passage to the front of member A, thence along the front of member A, thence through passage a⁵ to the rear of member A, thence across the rear and 45 through groove a⁶ to the front, thence across the front and through groove a⁷ to the rear, thence passing through passage a⁵ to the front of member A. The cord member then 50 passes around head a, beneath lip a' and through groove a² engaging the stocking between it and member A. Member B then extends in a substantially straight line across the front of member A passing beneath member B at y and y', then passing 55 partly around shank a³ beneath head a⁴. Member B ends in triangular loop b which

is in sliding engagement with the ordinary looped leather strap B' having the ordinary buckle b' for adjustment purposes. The strap B' is shown as extending around the 60 leg although it might engage any other suitable support such as a corset and at its end is formed with a loop b², the inside of which engages loop b³, the latter being preferably stitched to loop b² as indicated by 65 the dotted line at e. Loop b³ engages shank a³ and is prevented from slipping off therefrom by head a⁴.

In using my garter the edge of the stocking is placed over head a of the offset projection and is firmly clamped between the edges of the head and member B where the latter passes around said head and also between member B and groove a². Member B holds itself firmly clamped against the 75 stocking because when the portion above head a² is drawn upon all the rest of member B toward the knot at x is tightened and the portion of member B which extends in a substantially straight line from groove a² 80 to shank a³ is firmly clamped beneath those portions of member B indicated at y and y'. Putting the central passage through member A slightly off center enables me to run member B from groove a² to shank a³ 85 in a substantially straight line and this is preferable because it makes the device smooth and flat and prevents liability of kinking. It is preferable to run member B from the right edge of groove a² (as shown 90 in Fig. 2) to the left edge of shank a³ and when member B is loosened to remove the stocking it is desirable that member B be held in the position shown so that it will be 95 in said position when the garter is to be attached to the stocking and this is accomplished by that portion of member B which extends across the front of member A between groove a⁶ and groove a⁷ because said portion remains sufficiently taut to retain 100 member B so that it will run from the right of groove a² to the left of shank a³.

By providing a loose connection between loop b and strap B' I make sure that the pull on said strap will always be a central 105 one.

The head a⁴ may be at any desired distance from the body portion of member A as its main function is to prevent member B from slipping off from the shank but it 110 may be desirable to clamp member B beneath said head and this may be done by

making said distance slightly less than the sum of the diameters of member B and of the member forming loop b^3 .

It will be clear that the more strain there is on member B the more firm will be the clamping force exerted by member B itself.

The rigid connection between loop b^3 and loop b^2 makes sure that slipping will be avoided which is an advantage of importance.

10. What I claim is:—

1. A garter comprising two members to engage a stocking between them, one member having a body portion, an offset projection and a headed stud; and the other member being connected at one end to the first member, extending thence over said body portion and thence around said offset projection to grip the stocking between it and 15 said projection, said other member extending from said projection beneath the above-mentioned portion of itself which extends along said body portion, thence partly around said headed stud to engage a support, that portion of the second member extending from said projection to said stud being clamped between said body portion and said portion of itself which extends over said body portion to maintain the grip. 20

2. A garter comprising one member having a body portion with a headed stud near one end; and a second member coöperating with the first member at a distance from 25 said stud to grip the stocking, a leg-encircling band, said second member extending from said gripping point to and partly around said stud to engage said leg encircling band; said band carrying at its free 30 end a loop, the latter adapted to encircle said stud and clamp a portion of the second member beneath the head of the stud.

3. A garter comprising a member having a headed stud near one end, a grooved offset 35 projection and two passages extending from one face of said member through to the other face; and a second member knotted at one end, extending through one of said 40 passages, thence across one face of the first member, thence through the other of said passages, thence around one edge of the first member, thence across said face and around the other edge, thence through the second named passage, thence through said groove, 45 thence to said stud across said face and beneath that portion of itself which extends from edge to edge of said face, a support, said second member extending thence partly around said stud to engage one end of said 50 support, the latter being connected at its other end to said first member.

4. A garter comprising one member having a body portion with a headed stud near one end; a second member coöperating with 55 the first member at a point a distance from

said stud to grip the stocking, said second member extending from said gripping point to and partly around said stud and ending in a loop; a strap having at one end a loose connection with said loop to insure a central pull on said strap, said strap being adapted for connection to the stud to hold the garter in place.

5. A garter comprising a member adapted to engage a stocking and having a passage therethrough and having a body portion, a headed stud and an offset projection, a line from one edge of said projection to the opposite edge of said stud passing to one side of said passage; and a second member connected at one end to the first member, passing through said passage, thence around said body portion, thence again through said passage, thence around said projection, and extending from one edge thereof to the opposite edge of said stud and beneath that portion of itself which extends around said body portion.

6. A garter comprising two members to engage a stocking between them, one member having a body portion, an offset projection and a headed stud; and the other member extending along said body portion, thence around said body portion and thence around said offset projection to grip the stocking between it and said projection, said other member extending from said projection beneath the above-mentioned portion of itself which extends around said body portion and also beneath the above-mentioned portion of itself which extends along said body portion, thence partly around said headed stud to engage a support, that portion of the second member extending from said projection to said stud being clamped between said body portion and the above-mentioned portion of said second member which extends around said body portion and being also clamped between said body portion and the above-mentioned portion of said second member which extends along said body portion.

7. A garter comprising a member having a headed stud, a portion at a distance from said stud to engage the stocking and a passage extending from one face of said member through to the other face; and a second member connected at one end to the first member, passing through said passage, thence around one edge of the first member, thence across said member, thence around the other edge of said member, thence through said passage, thence to and around said portion of the first member to engage the stocking, thence to said stud beneath that portion of itself which extends across the first member, thence partly around said stud, a support connected with this end of the second member, said support terminating in a loop portion which encircles said stud and

clamps a portion of the second member beneath the head of said stud.

8. A garter comprising two members to engage a stocking between them, one member having a body portion with a passage therethrough and an offset projection, and the other member being connected near one end to the first member and extending thence along the body portion to and through 10 said passage, thence around the body portion, thence again through said passage, thence around said projection to engage the stocking, thence along said body portion and beneath that portion of itself which extends 15 around the body portion and also beneath that portion of itself which extends from said point of connection to said passage, and thence extending to engage a support.
9. A garter comprising two members to engage a stocking between them, one member having a body portion with a passage therethrough and an offset projection, and the other member being connected near one 20 end to the first member and extending thence along the body portion to and through said passage, thence around the body portion, thence again through said passage, thence 25

around said projection to engage the stocking, thence along said body portion and beneath that portion of itself which extends 30 around the body portion and also beneath that portion of itself which extends from said point of connection to said passage, the portion so extending beneath the two mentioned portions passing to one side of said 35 passage, and thence extending to engage a support.

10. A garter comprising two members to engage a stocking between them, one member having a body portion with a passage 40 therethrough, and the other being connected near one end to the first member and extending thence along the body portion to and through said passage, thence around the body portion, thence again through said passage, thence to engage the stocking between 45 itself and the first member, thence along said body portion and between the body portion and a portion of itself and thence extending to engage a support.
